UNITED STATES PATENT OFFICE

154,068

DESIGN FOR A FISHING ROD REEL MOUNT

Walter L. Rives, Jacksonville, Fla.

Application March 17, 1948, Serial No. 145,186

Term of patent 14 years

(Cl. D31—4)

To all whom it may concern:

Be it known that I, Walter L. Rives, a citizen of the United States of America, residing at Jacksonville, county of Duval, and State of Florida, have invented a new, original, and ornamental Design for Fishing Rod Reel Mounts, of which the following is a specification, reference being had to the accompanying drawing, forming a part thereof.

Figure 1 is a side elevational view of a fishing rod reel mount, showing my new design.

Figure 2 is a side elevation, opposite to that shown in Figure 1.

Figure 3 is a front elevation.

Figure 4 is a top plan view.

I claim:

The ornamental design for a fishing rod reel mount, as shown.

WALTER L. RIVES.
